JOSEPH PETERMÖLLER, OF GLASGOW, SCOTLAND, ASSIGNOR TO G. & J. WEIR, LIMITED, OF GLASGOW, SCOTLAND.

CONTROL DEVICE FOR ROTARY BOILER FEED-PUMPS.

1,129,009

Specification of Letters Patent. Patented Feb. 16, 1915.

Application filed September 14, 1914. Serial No. 361,710.

To all whom it may concern:

Be it known that I, JOSEPH PETERMÖLLER, a subject of the Emperor of Germany, residing at Cathcart, Glasgow, Scotland, have 5 invented certain new and useful Improvements in Control Devices for Rotary Boiler Feed-Pumps; and I do hereby declare the following to be a full, clear, and exact description of the invention, such as will enable others skilled in the art to which it 10 pertains to make and use the same, reference being had to the accompanying drawings, and to letters or figures of reference marked thereon, which form a part of this specification.

This invention relates to boiler feed pumps of the centrifugal or rotary pistonless type.

It is necessary that the pressure at the discharge of a boiler feed pump should be 20 in excess of the boiler pressure in order to overcome the frictional resistances in the pipes and the like between the pump and the boiler or boilers. These frictional resistances depend upon the velocity of the 25 water and are, therefore, influenced by the quantity of water discharged by the pump, and this fact is of special importance where the pump discharges through a long range of piping or through an economizer. It is, 30 therefore, desirable that the pressure available to overcome these resistances, *i. e.*, the excess of the pump discharge pressure over the boiler pressure should increase with the 35 quantity of water discharged by the pump.

The object of this invention is to provide a speed control device for a boiler feed pump of such a nature that the discharge pressure increases with the quantity of water discharged, and increases in such a manner as 40 to satisfactorily meet the increased frictional resistances.

This invention consists in means for attaining this object and is described in the following specification and clearly defined 45 in the annexed claims.

The invention is illustrated in the accompanying drawing.

Figure 1 illustrates the invention as applied to a steam-driven pump. Fig. 2 illustrates the invention as applied to an electrically-driven pump.

Referring in the first place to Fig. 1, *p* is a 50 rotary boiler-feed pump and *t* is a steam turbine which is directly coupled to and drives it. *a*, *b*, *c* is a convergent-divergent

nozzle on the water discharge passage from the pump. *d* is a small cylinder arranged adjacent to the live-steam pipe *e* which supplies the turbine *t*. *f* is a small pipe which connects the throat *b* of the convergent-divergent nozzle with the bottom of the cylinder *d*, and *g* is a pipe which connects the top of the cylinder *d* with the steam pipe *e*. *h* is a valve which controls the flow of steam to the turbine. This valve is connected by 60 the rod *g* with a piston *n* which works in the cylinder *d*.

The full area on the upper side of the piston *n* is exposed to the boiler pressure. The area of the under side of the piston, 70 diminished by the area of the rod *g*, is subjected to the pressure at the throat *b* of the convergent-divergent nozzle. The piston is therefore in equilibrium only when the pressure at *b* is slightly greater than the boiler 75 pressure. When the pressure at *b* tends to rise, the piston rises and throttles the steam supply to the turbine, so reducing the speed of the pump until equilibrium is established. When the pressure at *b* tends to fall, the 80 piston falls and admits more steam to the turbine, so increasing the speed of the pump until equilibrium is established.

The pressure at *c* is always greater than the pressure at *b*, but the difference between 85 the pressure at *c* and the pressure at *b* depends upon the quantity of water passing through the nozzle.

Let p_b represent the pressure at *b*. Let p_c represent the pressure at *c*. Let v_b represent 90 the velocity at *b*. Let v_c represent the velocity at *c*. Let s represent the specific density of water, *i. e.*, the mass per unit volume. Then, ignoring the work done against gravity which is negligible;

$$\frac{p_b}{s} + \frac{v_b^2}{2} = \frac{p_c}{s} + \frac{v_c^2}{2}$$

Therefore

$$p_c - p_b = \frac{v_b^2 - v_c^2}{2} \times s$$

The ratio of v_b to v_c is constant.
Let $v_b = c \times v_c$. Then

$$p_c - p_b = \frac{v_c^2}{2} \times s \times (c^2 - 1)$$

If p_b is maintained constant and just a little above boiler pressure, then the available pressure to overcome the frictional re- 115

sistances is approximately proportional to these resistances which vary very nearly as the square of the velocity.

When the pump is electrically driven, the device can be arranged as illustrated in Fig. 2. In this case the piston rod of the control cylinder is mechanically connected to a rheostat *r* which controls the supply of current to the electric motor *m* which drives the pump. The bottom of the cylinder *d* is, as before mentioned, placed in communication with the throat of the convergent-divergent nozzle by a pipe *f*, while the top of the cylinder is placed in communication by a water pipe *u* with a boiler or boilers fed by the pump.

When two or more pumps deliver into a common discharge pipe, each pump may, if desired, be provided with a convergent-divergent nozzle and with a control cylinder as hereinbefore described; or a single convergent-divergent nozzle may be provided on the common discharge pipe, and a single control cylinder connected to the neck of this single nozzle and employed to control all the pumps, or separate control cylinders may be connected to the neck of the single nozzle and each employed to control one of the several pumps.

It may in some cases be possible to substitute a diaphragm for the piston of control cylinder, the general action being the same; and the carrying of the invention into effect might otherwise be slightly modified in details.

Having thus described my invention, what I claim as new and desire to secure by Letters Patent is:—

1. In combination, a boiler, a rotary pump adapted to supply feed water to said boiler, a motor adapted to drive said pump, a convergent-divergent nozzle on the water-discharge passage of said pump, a control cylinder, a piston adapted to slide in said cylinder, means for placing one end of said cylinder under the pressure which exists in the throat of said nozzle, means for placing the other end of said cylinder under the pressure which exists in said boiler, means for controlling the supply of actuating fluid to said motor, and means whereby said piston can actuate said fluid-controlling means to reduce the supply of said fluid with an increase in the excess of pressure in the first-mentioned end of said cylinder over that in the second-mentioned end of said cylinder.

fluid with an increase in the excess of pressure in the first-mentioned end of said cylinder over that in the second-mentioned end of said cylinder.

2. In combination, a boiler, a rotary pump adapted to supply feed water to said boiler, a steam engine adapted to drive said pump, a steam pipe adapted to convey steam to the said engine for the purpose of driving it, a control valve on said steam pipe, a convergent-divergent nozzle on the water-discharge passage of said pump, a control cylinder, a piston adapted to slide in said cylinder, a pipe connecting one end of said cylinder to the throat of said nozzle, a pipe connecting the other end of said cylinder to the said steam pipe on the boiler side of said control valve, the said piston being connected to and adapted to actuate the said valve, the connection being such that an increase in the excess of pressure in the first-mentioned end of the said cylinder over that in the second-mentioned end acts to close the said valve.

3. In combination, a plurality of boilers, a plurality of rotary pumps adapted to supply feed water to said boilers, a common discharge pipe adapted to convey the water from said pumps to said boilers, a motor adapted to drive each of said pumps, a convergent-divergent nozzle on said common discharge pipe, a control cylinder, a piston adapted to slide in said cylinder, means for placing one end of said cylinder under the pressure which exists in the throat of said nozzle, means for placing the other end of said cylinder under the pressure which exists in said boilers, means for controlling the supply of actuating fluid to said motors, and means whereby said piston can actuate said fluid-controlling means to reduce the supply of said fluid with an increase in the excess of pressure in the first-mentioned end of said cylinder over that in the second-mentioned end of said cylinder.

In testimony whereof I have signed my name to this specification in the presence of two subscribing witnesses.

JOSEPH PETERMÖLLER.
